UNITED STATES PATENT OFFICE.

JOSEPH C. McEWEN, OF LOCHLOOSA, FLORIDA.

WEATHER-BOARD GAGE.

SPECIFICATION forming part of Letters Patent No. 280,494, dated July 3, 1883.

Application filed September 28, 1882. (Model.)

To all whom it may concern:

Be it known that I, JOSEPH C. McEWEN, of 5
Lochloosa, in the county of Alachua and State
of Florida, have invented a new and Improved
Weather-Board Gage, of which the following
is a full, clear, and exact description.

My invention consists of a stock to be fastened 10
below the last board nailed on by a clip
extending up behind said board, and by a
screw-point in the stock, on which stock there
is an adjusting-block by which to gage the
next board, a measure for setting it, and a lever
device for attaching the stock by the clip; 15
and the stock is provided with hooks on which
to hang the tools, to be used for convenience of
the workman, all as hereinafter fully de-
scribed.

Reference is to be had to the accompanying 20
drawings, forming part of this specification, in
which similar letters of reference indicate cor-
responding parts in all the figures.

Figure 1 is a front elevation of my improved 25
weather-board gage applied to the weather-
boards as in use. Fig. 2 is a side elevation of
the gage and section of the weather-boards.
Figs. 3 and 4 are details in section.

The stock consists of a suitable bar, *a*, of 30
wood, with a boss, *b*, at the back of the lower
end, the shoulder *c* of which is about as wide
as or a little wider than the lower edge of the
side or weather boards, *d*, to enable them to
rest on it, as shown in Fig. 2. The back *e* of 35
this boss is beveled to correspond with the
slant of the weather-boards, and to the upper
corner a thin steel clip, *f*, is attached, to be in-
serted between the lower edge of the last board
nailed on and the upper edge of the one below, 40
as shown in Fig. 2, so that the slight screw-pin
g, fitted in the stock, being screwed forward, so
as to force the pin into the board, will, together
with said clip, effect substantial connection of
the gage to the boarding. Along up the stock 45
there is a gage for the board to be nailed on,
consisting of the supporting-block *h*, adjust-
able up and down the stock by the clamp-nut
and screw *i* in the slot *j*, and the lever *k* and

link *l*. The block *h* alone may be used, with 50
its clamp *i*; but the lever is connected to it, to
facilitate the connection of the gage by press-
ing the clip *f* upward by use of the lever *k*,
whose short arm is placed over the last board
nailed on, and its long arm lifted to bring the
shoulder *c* snugly to the bottom of the weather- 55
board, whereupon the pin *g* is pressed into the
board below, and the gage thus firmly at-
tached. The lever and link *k l* can now be
swung forward through the slots *j* and *h* in
the bar *a* and block *h*, respectively, leaving the
upper face of the block *h* clear to receive the
next board to be nailed on and gage it to 60
proper position. Like the boss *b*, the block *h*
is beveled at the back, to correspond with the
slant of the boards. It is made adjustable up
and down for setting it for boards of different
widths. 65

A scale of measure is marked along one edge
of the stock at *m*, by which to set the gage *h*.

The screw-pin *g* is provided with a handle, 70
n, for turning it by hand, which I propose to
so construct that the saw *o* may be hung on it
by the handle; and I attach hooks *p* and *q*, on
which to hang the scratch-awl *t* and the scribe-
gage *u*, so that the workman may have them
ready to his hand.

It will be seen that this simple implement 75
will greatly assist in the accuracy and expedi-
tion of the work.

Having thus fully described my invention, I
claim as new and desire to secure by Letters
Patent— 80

The grooved stock *a*, having a boss, *b*, the
clip *f*, secured thereon, the screw *n*, provided
with a spur-point, *g*, therein, and a block, *h*,
provided with a set-screw, *i*, adjustably fitted
to the grooved stock, in combination with a 85
lever, *k*, and a link, *l*, connecting the same to
block *h*, as and for the purpose specified.

JOSEPH C. McEWEN.
